STOP MECHANISM FOR ROTARY CONTAINERS

Abraham Traube, Brooklyn, N. Y.

Application June 22, 1945, Serial No. 600,901

10 Claims. (Cl. 188—69)

1

This invention relates to stop mechanism for rotary containers, and more particularly to mechanism for the stopping and positioning of the rotary hollow drum or container of a washing or dry-cleaning machine of the type in which the drum or container is mounted to rotate about a horizontal axis within an outer shell or casing.

In such a machine, the door in the drum or container must be brought into register with the door opening in the outer shell, so that, after the shell door has been opened, the door in the drum may be swung outwardly into the shell-door opening, and the safety mechanism forming the subject-matter of the present invention is designed to stop and accurately position the drum for the opening of its door to permit of loading and unloading of the drum.

One object of the present invention is to provide improved safety stop mechanism whereby a slowly rotating drum may be brought to rest and then held in its proper position with respect to the outer shell.

A further object is to provide improved means actuated by a handle from the front of the shell whereby a buffer and gate device is brought into cooperative relation with a member on the rotary drum whereby the latter is halted and held in position. Another object is to provide stop mechanism with an operating handle and buffer and gate mechanism whereby the device is held in the inoperative position; and still another object is to provide a slide having latch devices for retaining the locking means in the inoperative position.

With these and other objects in view, my invention consists in the novel construction and arrangement of parts hereinafter described, illustrated in the accompanying drawings and particularly pointed out in the appended claims, it being understood that various changes may be made in the construction, arrangement, and operation without departing from the spirit of the invention or sacrificing any of the advantages thereof.

In the drawings,

Fig. 1 is a side view—shown partly in section—of the locking mechanism in the operative position;

Fig. 2 is a similar view showing the mechanism in the inoperative position;

Fig. 3 is a view looking on the inside face of part of the locking mechanism;

Fig. 4 is an outside front-face view corresponding to Fig. 1; and

Fig. 5 is a detail view being an inverted plan

2

showing certain of the parts of the mechanism in two positions corresponding to Figs. 1 and 2.

The safety stop mechanism is designed for application to a machine of the type having a rotary member that must from time to time be brought to rest and accurately positioned and, referring to the drawings, the mechanism is shown applied to a dry-cleaning or washing machine comprising an inner drum or container 10 adapted to rotate about a horizontal axis within a fixed outer shell 11 having a sliding door 12 of arcuate form carried in guide groove 13 at the front of the shell; and the arrangement is such that when the drum 10 has been stopped and accurately positioned and when the door 12 is opened, hinged doors in such drum may swing outwardly through the door openings uncovered by the doors 12, so that free access is given to the interior of the drum for loading and unloading.

The rotary drum 10 is provided—see Fig. 1—with a projecting stop pin 14 and the locking and positioning mechanism is carried by a casing 15 secured on the outer face of the stationary shell 11. When the parts are in the position shown in Fig. 1 the drum 10 is accurately positioned and held stationary so that the doors of the shell and of the drum may be opened to permit loading or unloading of the drum. Enclosed within the casing 15 is a movable plate 16 having two parallel inwardly projecting flange plates 17 with a connecting web member 18 carrying a one-way spring gate device consisting of two pivoted arms 19 provided (see Fig. 3) with projecting pins 20 which may extend through openings 21 in the flange plates 17. The pivoted arms 19 are normally pressed towards each other by springs 22 on the said pins 20 and when the stop mechanism is in the position shown at Fig. 1 and the drum is turned in a counter-clockwise direction the stop pin 14 forces the arms 19 away from each other until the stop pin reaches the position shown at Figs. 1 and 3. On further rotation of the drum 10 the stop pin 14 engages a cross bar 23 which acts as a spring bumper and arrests the motion of the drum. The bar 23 is provided with end pins 24 for which slots 25 in the flange plates 17 serve as guides. A second cross-bar 26 is provided with similar end pins 27 engaging the same slots 25, and pins 28 secured to the cross bar 23 extend freely through openings in the cross bar 26 while springs 29 carried on said pins 28 are in compression between the said cross-bars 23, 26, so that the necessary spring action is provided to absorb the

momentum of the drum 10 which is imparted to the cross-bar 23 by the stop pin 14, and the gate formed by the arms 19 prevents reverse movement of the pin 14 by engagement thereof with the ends of said arms.

The said plate 16 has projecting outwardly therefrom a central pin 30 which extends freely through the casing 15 and through a slot 31 in a slide member 32 and on its outer extremity the said pin 30 has a pivot pin 33 engaged by the forked end 34 of a hand-lever 35 having a fulcrum pin 36 which is carried by a bracket 37 secured on the casing 15 and extending through a slot 38 in the said slide member 32. The hand-lever 35 has a slot 39 for the passage of the fulcrum pin 36, so that counter-clockwise movement of the lever 35 about the fulcrum pin 36 moves the plate 16 with its flange plates 17 and stop-pin-engaging members from the locking position shown in Fig. 1 to the inoperative position shown at Fig. 2, where the flange plates 17 are shown clear of the path of the locking pin 14.

The mechanism is held in the position shown at Fig. 1 by means of springs 40 in compression between the casing 15 and the plate 16 and extending through each spring 40 is a guide pin 41 which passes freely through a hole in the casing 15 and has one end anchored in the plate 16 while the opposite end carries a collar 42 whose underside may be engaged by the outer edges 43 on the half-collars 44 projecting outwardly from the slide member 43 which latter has its lower extremity 45 formed as a handle by means of which it may be pulled downwardly into the position shown at Fig. 2 (if it does not fall by gravity) after the hand-lever 35 has been operated to withdraw the stop mechanism from the position of Fig. 1. The guide pins 41 pass through slots 46 in the slide 32 so that the latter may be raised and lowered to bring the half-collars 44 into or out of their locking position.

The slide plate 32 is also provided at the sides of the slot 31 above referred to with cheeks 47 having outer extremities 48 for cooperation with projections 49 on the sides of a boss 50 on the outer part of the said pin 30. When the mechanism is in the inoperative position shown at Fig. 2 the two projections 49 rest upon the side cheeks 47 and to bring the mechanism into operation the hand-lever 35 must be turned slightly in a counter-clockwise direction to cause the projections 49 to release the extremities 48 of the cheeks 47 after which the slide member 32 is raised by means of its handle 45 from the position of Fig. 2 to the position of Fig. 1 and the hand-lever 35 is then permitted to turn in a clockwise direction under the action of the springs 40.

Referring particularly to Figs. 4 and 5, the said boss 50 on the pin 30 carries a pair of oppositely disposed pivot-pin-receiving members 51 one or each of which may carry a pivot-pin 52 for engagement with the forked end 53 of a double-armed lever 54 having a slot 55 to receive a fulcrum pin 56 carried by a fixed bracket 57 mounted on the shell 11 of the machine. The free end 58 of the lever 54 is adapted to move into or out of the path of a projection 59 formed on the arcuate door 12 of the shell 11, and the arrangement is such that when the mechanism is in the operative position shown in Fig. 1 the lever 54 is in the position shown in full lines at Fig. 5 and the door 12 is free to open, while the dotted lines show the position of the lever 54 preventing opening of the door 12 in the shell 11 while the mechanism

is in the inoperative position of Fig. 2 and the drum 10 is free to rotate.

In the case of machines having two separate door openings in the shell for giving access to corresponding doors in the drum, the stop mechanism may be mounted on the front of the shell between such shell door openings and with reference to Figs. 4 and 5 door-locking mechanism may be provided to extend to the right as well as to the left instead of to the left only, as shown in these figures where the mechanism is adapted for use with a single shell door opening giving access to a single or double door in the drum.

Although the drawings and the above specification disclose the best mode in which I have contemplated embodying my invention, I desire to be in no way limited to the details of such disclosure, for in the further practical application of my invention many changes in form and construction may be made as circumstances require or experience suggests without departing from the spirit of the invention within the scope of the appended claims.

What I claim is:

1. Mechanism of the character described for stopping and positioning a rotary container within a fixed outer shell, comprising a one-way spring gate and a spring bumper, a projection on the container for co-operation with the said gate and bumper, and means for moving the gate and bumper into the path of said projection to stop and position the container by the engagement of said projection with said bumper.

2. Mechanism of the character described for stopping and positioning a rotary container within a fixed outer shell, comprising a one-way spring gate and a spring bumper, a projection on the container for co-operation with the said gate and bumper, means for moving the gate and bumper into the path of said projection to stop the container by the engagement of said projection with the bumper, and means for preventing the opening of the shell while the gate and bumper are not in the said path.

3. In a machine having a rotary member rotating within a stationary shell, mechanism for stopping and positioning the rotary member within the shell, comprising a stop device on the rotary member, spring-actuated pivoted gate members for engagement by said stop device, a spring bumper for arresting the movement of the stop device after release by said gate members, means for moving said gate members and bumper into and out of the path of the stop device, and locking means for retaining the bumper and gate members out of said path.

4. In a washing or dry-cleaning machine having a rotary cylindrical container enclosed within a stationary shell with doors in the shell and in the container adapted to register with each other for loading and unloading the container, mechanism for stopping and positioning the container for loading and unloading, comprising a stop device on the container, pivoted gate members for engagement by the stop device, spring means resisting movement of the gate members for the passage of said stop device, spring bumper means for arresting movement of said device after passage through said gate, means for moving the mechanism into and out of the path of said stop device, and means for locking the shell door when the gate and bumper are out of the path of said stop device.

5. In a machine having a rotary member rotating within a stationary shell, mechanism for

stopping and positioning the rotary member within the shell, comprising a stop device on the rotary member, two spring-actuated pivoted gate members for engagement by said stop device, a spring bumper for arresting the movement of the stop device after release by said gate members, spring means for moving said gate members and bumper into the path of the stop device, hand-actuated means for retracting the gate members and bumper from said path, and locking means for retaining the mechanism in such retracted position.

6. In a washing or dry-cleaning machine having a rotary container for the material being cleaned or washed, means for stopping and positioning the rotary container for loading and unloading, comprising a stop device on the container, a spring bumper for engaging the stop device and arresting the motion of the container, spring-actuated gates for preventing counter-rotation of the container after engagement by said bumper, means for retracting the bumper and gates from position for engagement by the stop device, and a gravity-actuated slide-member for holding the mechanism in the retracted position.

7. In a washing or dry-cleaning machine having a rotary cylindrical container enclosed within a stationary shell with doors in the shell and in the container adapted to register with each other for loading and unloading the container, mechanism for stopping and positioning the container for loading and unloading, comprising a stop device on the container, pivoted gates for engagement by the stop device, springs for resisting movement of the gates for the passage of said stop device, a spring bumper for arresting movement of said device after passage through said gates, spring means for moving the gates and bumper into the path of said stop device, a hand lever on the shell for retracting the gates and bumper from said path against the action of said spring means, and means whereby the shell door is prevented from opening when the stop mechanism is in the retracted position.

8. Means for stopping and positioning the rotary container of a dry-cleaning or washing machine to cause the container doors to register with the doors of the outer shell, comprising a stop pin on the container, retractable gates and a bumper for engaging said stop pin, guides mounted on the shell for carrying the gates and bumper, spring means normally pressing said gates and bumper into the path of said stop pin, lever means for moving the gates and bumper in-

to retracted position against the action of said spring means, and an independently actuated locking device for holding the gates and bumper in the retracted position.

- 5 9. Means for stopping and positioning the rotary container of a dry-cleaning or washing machine to cause the container doors to register with the doors of the outer shell, comprising a stop pin on the container, retractable pivoted gates and a spring bumper for engaging said stop pin, guides mounted on the shell for carrying said gates and bumper, spring means normally holding the gates and bumper in the path of said stop pin, means for retracting the gates and bumper against the action of said spring means, and locking means actuated by said retracting means for preventing opening of the door of the outer shell while the gates and bumper are in the retracted position.
- 10 10. Means for stopping and positioning the rotary container of a dry-cleaning or washing machine to cause the container doors to register with the doors of the outer shell, comprising a stop pin on the container, retractable spring members for engaging said stop pin, guides mounted on the shell for carrying said spring members, spring means normally holding said spring members in the path of the stop pin, lever means for retracting the spring members against the action of the said spring means, a slide device for locking the said spring members in the retracted position, and a locking device actuated by said lever means for preventing opening of the door of the outer shell while the spring members are in their retracted position.
